US00D826711S

(12) **United States Design Patent** (10) Patent No.: **US D826,711 S**
(45) Date of Patent: **** Aug. 28, 2018**

(54) **CARTON**

(71) Applicant: **Graphic Packaging International, Inc.**, Atlanta, GA (US)

(72) Inventors: **Harmen Boersma**, Heerenveen (NL); **Ana Gonzalez**, Barcelona (ES); **Esteve Rovira Porta**, Barcelona (ES); **Brian Smalley**, Bristol (GB); **Jon Thompson**, Bristol (GB); **Marie Zix**, Avion (FR)

(73) Assignee: **Graphic Packaging International, LLC**, Atlanta, GA (US)

(**) Term: **15 Years**

(21) Appl. No.: **29/582,962**

(22) Filed: **Nov. 1, 2016**

Related U.S. Application Data

(63) Continuation of application No. 15/286,963, filed on Oct. 6, 2016.

(51) **LOC (11) Cl.** **09-03**

(52) **U.S. Cl.**

USPC **D9/432**

(58) **Field of Classification Search**

USPC D3/201, 203.1, 203.5, 203.6; D7/601, D7/602, 609; D9/414-416, 418-423, D9/425, 426, 430-436, 444, 455-457, D9/499

CPC B65D 71/36

(57) **CLAIM**

The ornamental design for a carton, as shown and described.

DESCRIPTION

FIG. 1 is a perspective view of a carton.

FIG. 2 is a left elevation view of the carton of FIG. 1, the right elevation view being identical.

FIG. 3 is a front elevation view of the carton of FIG. 1, the rear elevation view being identical.

FIG. 4 is a top plan view of the carton of FIG. 1; and,

FIG. 5 is a bottom plan view of the carton of FIG. 1.

The claim is directed to the shaded surfaces only. All evenly-spaced broken lines depict environmental subject matter only that forms no part of the claimed design.

1 Claim, 5 Drawing Sheets
